UNITED STATES PATENT OFFICE

GEORGE E. WADSWORTH, OF ERLANGER, KENTUCKY, ASSIGNOR TO THE GEORGE B. WADSWORTH COMPANY, OF CINCINNATI, OHIO, A CORPORATION OF OHIO

SAFETY FUSE BLOCK

Application filed September 8, 1930. Serial No. 480,386.

My invention is directed to the provision of a self-contained fusible switch equipped with means for preventing access to the fuse receptacle when the switch is in closed position and means for preventing the closing of the switch so long as the fuse receptacle is accessible.

An object of my invention therefore is to provide a device comprising a switch or fuse receptacle and the aforementioned safety means in one unit which so far as its operation goes is independent of any other structure such as an enclosing box or receptacle.

Another object of my invention is to simplify the construction of such devices and to make them more economical of manufacture.

A third object of my invention relates to the use of a rotary switch which is desirable in structures of this character by reason of its proportionately greater throw and greater safety.

Still another object of my invention is the provision of a construction in which there is but one part to be moved by the operator, which part serves both as a cover for a fuse receptacle and as a knob for operating the switch.

These and other objects of my invention which will be pointed out hereinafter or will be obvious to one skilled in the art upon reading these specifications I accomplish by that certain construction and arrangement of parts of which I shall now describe a preferred embodiment, reference being made to the drawings which accompany this specification.

In the drawings:

Figure 1 is an isometric view with a portion cut away of my assembled device.

Figure 2 is a sectional view thereof.

Figure 3 is an isometric view of the switch receptacle column and the cover in assembled relationship.

Figure 4 is an elevation of my device with the cover open.

Figure 5 is a plan view of the base from beneath with certain parts shown in dotted lines.

Figure 6 is an elevation and plan of the safety cover.

Figure 7 is a plan and section of the upper portion of the rotating switch member.

Figure 8 is a plan view from beneath and a section of the fuse receptacle column.

Figure 9 is a plan view of a section of the lower part of the rotary switch mechanism.

Figure 10 is a plan view of the base from above with the terminals and switch contacts shown.

Figure 11 is a bottom plan view of a modified form of mounting block showing one arrangement of electrical connections.

Figure 12 is a bottom plan view of the block shown in Figure 11 showing a different wiring arrangement.

Figure 13 is a bottom plan view of the block shown in Figures 11 and 12 showing a still different wiring arrangement.

Briefly in my invention I provide a base 1 of insulating material with an upstanding central column 2 which contains a fuse receptacle; about this column I provide a collar indicated generally at 3 which bears contact members forming part of a rotary switch, the corresponding contact members being located upon the base. Then I provide a cover 4 for the fuse receptacle portion and I provide means on the cover for operating the rotary switch and means on the fuse receptacle column controlling the operation of the cover whereby the safety features referred to are attained, as I shall now describe in detail.

The base 1 is a block of insulating material of suitable size having holes 5 for the passage of screws or bolts whereby it may be fastened to a panel board or within a box. Mounted centrally of this base is a column of insulating material 2. The manner of the mounting of this column in the preferred embodiment shown, will be taken up hereinafter in connection with the electrical connections. The column 2 is mounted non-rotatably upon the base, and it is hollowed out as best shown at 6 in Figure 8 to provide space for a fuse receptacle. Grooves 7 are made at opposite sides of the column which terminate short of the top thereof forming shoulders 8 at the top of the column. The grooves 7 connect with circular grooves 9 which in the embodiment shown are about the length of a quadrant of

a circle and terminate in shoulders 10. At the top of the column there may be provided, if desired, peripheral projections 11 oppositely disposed and also of a length substantially equivalent to the quadrant of a circle. This particular construction of the central column controls the movement of the cover which is the operating device or knob of my mechanism; and the cover will next be 10 scribed, whereupon the relationship of the two and the way in which the column controls the movement of the cover will be pointed out.

The cover 4 comprises a knob of insulating material, the upper part of which may be beveled and knurled as at 12 if desired and which is hollowed out internally as at 13 to provide a cap for the fuse receptacle and a space into which the top of a fuse in the receptacle may extend. The cover is provided with two metallic arms 14 which may conveniently both be part of a U-shaped strip of metal as shown having a portion 15 extending into the cap and held as by means of 20 screws or rivets 16. The arms 14 are of a distance apart substantially equal to the main diameter of the fuse receptacle column 2 so that the column itself might rotate between the arms; but the arms have turned over portions 17 at their lower ends. These turned over portions are adapted to enter the grooves 7. If the column 2 will be imagined as mounted upon the base 1, it will now be clear how the movement of the cover is controlled 25 thereby. The turned over portions 17 ride in the grooves 7, and the cover may therefore be withdrawn as shown in Figure 3, to the extent of the movement permitted by the said grooves. When however the turned over portions 17 abut the shoulders 8, the cover cannot further be withdrawn. When the cover is pushed down as far as it will go (see Fig. 3), it may then be rotated in a clockwise direction through a quarter of a 30 circle, the turned over portions 17 then riding in the peripheral grooves 9. Movement in this direction however will be stopped when the turned over portion 17 abuts the shoulders 10, and this position of the cap is 35 shown very clearly in Figure 1. When the cover has been rotated in a clockwise direction as shown in this figure, it may not then be pulled outwardly because the turned over portions 17 of the arms on the cover strike 40 the tops of the grooves 9 and inhibit such motion. When the cover is withdrawn however in the position shown in Fig. 3, it may not then be rotated because the grooves 7 hold the turned over portion 17 of the cover 45 against such rotation. It will now be clear that if I provide about the fuse receptacle column 2 a collar which comprises a rotary switch, and I provide means whereby the arms 14 may operate this switch, and if I arrange that the switch will be open when in a

position determined by the arms as shown in Figure 3, I will have attained the safety features which are an object of my invention. With the cover and column in the position of Figure 3, if I desire to close the switch I 70 must first thrust the cover home and then rotate it in a clockwise direction. When this is done, the switch will be closed and the mechanism will be as shown in Figure 1, but the cover cannot be opened until the switch 75 is again rotated to the off position.

The collar 3 may be made if desired in one piece but is more conveniently made in two pieces as shown in Figures 7 and 9. The lower portion is a thick ring of insulating substance 3a and the upper portion a thinner ring 3b with a flange 18 which is useful in forming a satisfactory closure when my device is installed in a switch box provided with a hole through which the cap 4 may extend. Both parts of the rotating collar 3a and 3b are provided with grooves 19 which are continuous, and which hold the arms 14 of the cover. The arms 14 operating in the said 80 grooves serve to rotate the collar when the cap is turned.

Having thus described the mechanical structure of the several operating parts of my device, I will now describe the electrical parts and the current connections. Upon the base I provide a terminal 20 of the usual type, provided with a current conducting metallic strap 21 which passes down through the base and ends in a position beneath the central part of the fuse receptacle column 2. In the hollowed out portion 6 of the fuse receptacle column I provide the threaded portion 22 of a fuse receptacle and a central contact member 23 which in this case may be in the form of a nut. A bolt 24 passes first from beneath through the strap 21, then through a hole centrally of the base, then through a hole centrally of the fuse receptacle column and is screwed into the nut 23. Thus current may be conducted from the terminal 20 through the strap 21 and the bolt 24 to the central contact member 23 of the fuse receptacle. 90

By this means also the bolt 24 serves to hold the fuse receptacle column to the base. 100

The threaded portion of the fuse receptacle 110 22 is connected by means of bolts 25 to a bifurcated strap 26 which has two arms 26a and 26b. This construction is advantageous in that the strap 26 is connected to the column at two points so as to be non-rotatable with reference thereto. It will be understood of course that the portions 26a and 26b are separated from the bolt 24 so that there is no electrical contact between them excepting through a fuse plug screwed into the receptacle. The base is hollowed out as at 27 to accommodate the bifurcated portion of the strap 26 and as at 28 to accommodate the elongated portion thereof and it will now be 120 125 130

seen that whereas the bolt 24 serves to mount the column upon the base, the strap 26 will serve the auxiliary function of preventing the rotation of the column with reference to the base. The strap 26 terminates in the spring contact 29 of a rotary switch. A terminal 30 is also mounted upon the base and bears a spring contact 31 serving as the second contact point of the rotary switch. Contact members upon the rotating part of the switch are conveniently formed by embedding a strap of metal 32 in the lower portion 3a of the collar, which strap terminates in exposed contact portions 33 and 34 adapted when the switch is in closed position to bridge the electrical gap between contacts 29 and 31.

In use 30 is a line terminal and 20 is a load terminal. The path of current between the said terminals may be traced as follows: from terminal 30 through contact member 31 to contact member 34, through strap 32 to contact member 33, thence to contact member 29, through strap 26 and bolts 25 to the screw shell of the fuse receptacle, through a fuse therein to the central contact point thereof 23, through bolt 24 to strap 21 and terminal 20.

The construction and operation of my device will now be clear. It will be evident that modifications may be made in it to adapt it to various uses all without departing from the spirit of my invention. As exemplary but without limitation, a different type of fuse receptacle may be used, or a different type of mounting of the column 2 upon the base 1 may be chosen. All electrical connections to the fuse receptacle may be made beneath the base. My reasons for making the column 2 and the base separate and for making the two portions of the collar 3 separate are largely concerned with convenience in molding the several parts since it is difficult in any molding operation to produce accurate under cut portions. By making the two parts of the collar separate however, and by locating the contact members 29 and 31 at less than 180° apart, I have provided a structure in which, when the switch is open as would be the case when the cover is in the position shown in Fig. 3, I may manually rotate the lower part 3a of the collar to a position 180° removed from its operating position, thereby locking the switch open, so long as a box or other cover prevents access to the portion 3a. When locked open as described, the cover may be opened or closed and the switch rotated as usual but the current will not be on in any position.

In Figures 11, 12 and 13 I have shown a modified type of mounting base, and I have also illustrated several different methods of wiring up the base for obtaining different electrical connections. It will be noted that in each of the modifications the line from the

power supply is connected to the terminal clip indicated at 29a.

Referring first to Figure 11, the current passes to the electrical connections of the block as follows: The line wire is connected to the terminal clip 29a and when the switch is turned on so that the metal strap 32a, as indicated in dotted lines, forms a contact between the terminal clip 29a and the terminal clip 30a, a wire such as is indicated at 36 may be connected to a meter and a wire 37 connected from the meter to the terminal 20a. At 21a I have indicated an angular strap which fits within the groove in the under surface of the mounting base and forms a contact with the central connector for the fuse. The current passes from the peripheral contact clips through the angular strap 21b to the load line terminal 20b. It will be noted that in this modification there is a double break in the switch between the line terminal and the motor. In some localities such an arrangement of electrical connections is required by the underwriters' regulations.

In Fig. 12 I have shown an arrangement in which the line wire is connected to the terminal 29a. When the switch is on the current passes through the strap 32 in the collar 3a to the terminal clip 30a. By inserting an angular strap 21b which, it will be noted, is the same shape and size as the strap 21b shown in Fig. 11, a contact will be formed with the peripheral clips of the fuse. From the center of the fuse a connection is then established through an angular strap 21 to the terminal 20a which in this instance is the load terminal from which wires can be connected to the various electrical apparatuses to be operated.

In Figure 13 I have shown a still further modification in which the line is connected to the terminal clip 29a and when the switch is on the current passes through the strap 32a to the terminal clip 30a. By inserting a strap 21c in the under surface of the base a connection is established with the terminal 20a. An angular strap 21a conducts the current to the medial connection to the fuse. From the peripheral fuse clips an angular strap 29b may be employed to conduct the current to the terminal 20d which in this instance becomes the load terminal.

The advantages of the electrical connections indicated in Fig. 13 over those shown in Fig. 12 consist in the fact that in Fig. 13 the switch and fuse assembly can have the line wire to the load wire connected through the same side of the box. It will be understood that the base members 1a are ordinarily mounted in a meter box with the cover member extending through an annular opening in the box so that the electrical connections to the box in which the switch is mounted are likely to be of considerable importance.

A further modification which I have shown

- in the blocks indicated in Figs. 11 to 13 are slots 38 through which the bent over ends of the arms 14 extend to limit the outward reciprocating movement of the cover member 4.
- 5 Other modifications in which different electrical hook-ups may be achieved by positioning the straps 21a, 21b and 21c within the grooves in the under surface of the base will readily occur to those skilled in the art.
- 10 Having thus described my invention, what I claim as new and desire to secure by Letters Patent, is:—
1. In a fusible double break switch mechanism a base of insulating material and an upstanding column thereon, said column bearing a fuse receptacle, a collar surrounding said column and forming the operating portion of a switch, and a cover for said fuse receptacle, means on said cover to operate said collar and means on said base to control the movement of said first mentioned means.
  2. In a fused switch a base of insulating material and an upstanding column thereon bearing a fuse receptacle, a cover for said fuse receptacle, a collar surrounding said column and forming the operating part of a switch, said cover adapted to operate said switch and means on said column to control the operation of said cover.
  3. In a fused switch a base of insulating material and an upstanding column thereon bearing a fuse receptacle, a cover for said fuse receptacle, a collar surrounding said column and forming the operating part of a switch, said cover adapted to operate said switch and means on said column to control the operation of said cover, said cover slideable with reference to said column, and said means adapted to inhibit the rotation of said cover when said cover has been slid upwardly, and to inhibit the sliding of said cover when said cover has been rotated to a given position.
  4. In a fused switch mechanism a base of insulating material and an upstanding column thereon bearing a fuse receptacle, a collar surrounding said column and rotatable with reference thereto forming the operating part of a switch, and a cover for said fuse receptacle, said cover having arms to operate said collar and means on said base to control the operation of said arms in two directions.
  5. In a fused switch mechanism a base of insulating material and an upstanding column thereon bearing a fuse receptacle, a collar surrounding said column and rotatable with reference thereto forming the operating part of a switch, and a cover for said fuse receptacle, said cover having arms to operate said collar, grooves longitudinally of said column terminating in peripheral grooves at the base thereof, arms on said cover adapted to operate said collar and having portions riding in said grooves where-
6 by said cover may be withdrawn but not ro-
7 tated when said portions lie in the longitudinal parts of said grooves, and rotated but not withdrawn when said portions lie in the peripheral parts of said grooves.
  6. In a fused switch mechanism a base of insulating material and an upstanding column thereon bearing a fuse receptacle, a collar surrounding said column and rotatable with reference thereto forming the operating parts of a switch, and a cover for said fuse receptacle, said cover having arms to operate said collar, grooves longitudinally of said column terminating in peripheral grooves at the base thereof, arms on said cover adapted to operate said collar and having portions riding in said grooves whereby said cover may be withdrawn but not rotated when said portions lie in the longitudinal parts of said grooves, and rotated but not withdrawn when said portions lie in the peripheral parts of said grooves, the longitudinal parts of said grooves terminating in shoulders to limit the outward motion of said arms.
  7. In a fused switch mechanism a base of insulating material and an upstanding column thereon bearing a fuse receptacle, a collar surrounding said column and rotatable with reference thereto forming the operating part of a switch, and a cover for said fuse receptacle, said cover having arms to operate said collar, grooves longitudinally of said column terminating in peripheral grooves at the base thereof, the arms on said cover having portions riding in said grooves whereby said cover may be withdrawn but not rotated when said portions lie in the longitudinal parts of said grooves, and rotated but not withdrawn when said portions lie in the peripheral parts of said grooves, the longitudinal parts of said grooves terminating in shoulders to limit the outward motion of said arms, contact members mounted on said base, contact members mounted on said collar, terminals on said base and electrical connections therebetween whereby a circuit may be formed between said terminals through said switch and said fuse receptacle.
  8. In a fused switch mechanism a base of insulating material, an upstanding central column of insulating material bearing a fuse receptacle, a collar surrounding said fuse receptacle and bearing contact members, contact members mounted on said base, one of said members being connected to a terminal device and the other to said fuse receptacle, said collar and associated parts forming a rotary switch, a second terminal on said base also connected to said fuse receptacle, a cover for said fuse receptacle, means on said cover for operating said collar as a switch upon rotation of said cover, said cover being slideable with respect to said column and means on said cover and said column to inhibit the sliding thereof when said switch is closed and to in-

- hibit the closing of said switch when said cover has been slid outwardly so as to expose said fuse receptacle.
9. In a fused switch assembly having a double break switch between line and load terminals thereof, a base of insulating material having grooves in the under surface thereof, connector bars shaped so as to fit in said grooves and establish connections between said terminals and fuse, said base having terminals at the corners thereof, and said grooves being so arranged that similarly shaped connector bars may be employed for establishing line and load connections for different circuits through said switch and fuse. 70
10. In a barrel type switch having a fuse arranged therein between line and load terminals, a double break switch between a line terminal and a connection to said fuse, a mounting base of insulating material having grooves therein, said grooves being shaped so that conductive straps may be secured therein in different circuit arrangements. 75
11. In a barrel type switch having a fuse arranged therein between line and load terminals, a double break switch between a line terminal and a connection to said fuse, a mounting base of insulating material having grooves therein, said grooves being shaped so that conductive straps of similar size and shape may be secured therein in different circuit arrangements. 80
12. In a switch assembly having a fuse arranged therein between line and load terminals of said switch fuse contact straps, a double break switch between a line terminal and a connection to said fuse contact straps, a mounting base of insulating material having grooves therein for receiving said contact straps, and means for mounting said straps in said grooves for the purpose described. 85
13. In a switch assembly having a fuse arranged therein between line and load terminals of said switch fuse contact straps, a double break switch between a line terminal and a connection to said fuse contact straps, a mounting base of insulating material having grooves therein for receiving said contact straps, and means for mounting said straps in said grooves so as to provide connections for a load terminal on the same or the opposite side of said assembly relative to the line terminal. 90
14. In a fuse block for electric circuits, a fuse connection, a double break switch, operating means for said switch comprising a cover for said fuse connection, said means movable in a rotary manner to operate said switch and in a reciprocating manner to uncover said fuse connection, means for preventing the reciprocation of said cover during "on" position of said switch. 95
15. In a fuse block for electric circuits, a fuse connection, a double break switch, oper- 100
- ating means for said switch comprising a cover for said fuse connection, said means movable in a rotary manner to operate said switch and in a reciprocating manner to uncover said fuse connection, means for preventing the reciprocation of said cover during "on" position of said switch, and connections between said double break switch and said fuse. 105
16. In a fuse block for electric circuits, a fuse connection, a double break switch, operating means for said switch comprising a cover for said fuse connection, said means movable in a rotary manner to operate said switch and in a reciprocating manner to uncover said fuse connection, means for preventing the reciprocation of said cover during "on" position of said switch, and means for securing conductive straps in said block to provide a load terminal on the same or on an opposite side of the side of said block on which the line terminal is mounted. 110
17. In a fusible double break switch mechanism a base of insulating material and an upstanding column thereof, said column bearing a fuse receptacle, a collar surrounding said column and forming the operating portion of a switch, and a cover for said fuse receptacle, means on said cover to operate said collar and means on said base to control the movement of said first mentioned means, said base being provided with grooves and straps adapted to seat in said grooves and to connect the terminals of said mechanism so that the position of the load terminal may be varied. 115
18. In a fusible double break switch mechanism a base of insulating material and an upstanding column thereon, said column bearing a fuse receptacle, a collar surrounding said column and forming the operating portion of a switch, and a cover for said fuse receptacle, means on said cover to operate said collar and means on said base to control the movement of said first mentioned means, said base being provided with grooves and straps adapted to seat in said grooves in different positions so that one arrangement permits a meter to be connected between the double break switch and said fuse receptacle. 120
